UNITED STATES PATENT OFFICE.

WILLIAM HAINSWORTH, OF PITTSBURG, PENNSYLVANIA.

MANUFACTURE OF STEEL BLOOMS AND BILLETS.

SPECIFICATION forming part of Letters Patent No. 268,222, dated November 28, 1882.

Application filed November 4, 1881. (No model.)

To all whom it may concern:

Be it known that I, WILLIAM HAINSWORTH, of Pittsburgh, county of Allegheny, State of Pennsylvania, have invented or discovered a new and useful Improvement in Manufacture 5 of Steel Blooms and Billets; and I do hereby declare the following to be a full, clear, concise, and exact description thereof, reference being had to the accompanying drawings, making a 10 part of this specification, in which—like letters indicating like parts—

Figure 1, Sheet 1, is a side elevation, partly in vertical section, of an apparatus illustrative of my present invention. Fig. 2 is a top or 15 plan view thereof. Fig. 3 is a vertical transverse section in the plane of the line $x\bar{x}$, Fig. 1. Fig. 4 is an end elevation of the crane-car employed, and a sectional view of the tracks and one mold. Fig. 5, Sheet 2, is a side elevation, 20 to an enlarged scale, of one of the roll-cars employed, as in Fig. 1, and a longitudinal vertical section of another, as also the line of the molds. Fig. 6 is a top or plan view, to a like 25 scale, of one of the roll-cars, but with the middle set-screws sectioned on one side in the line $x'\bar{x}'$, and on the other side in the line $x^2\bar{x}^2$ of Fig. 5, and Fig. 7 is a vertical cross-section in the plane of the line $x^3\bar{x}^3$ of Fig. 6.

In the manufacture of ingot iron and steel 30 it has been usual to cast the material into upright ingot-molds, from which the ingots were removed as soon as chilled, and then, after being reheated, to pass them through a train of blooming-rolls, so as to produce what are known 35 as "blooms." This method of operation involves considerable loss. The metal chills and solidifies on the outside first, and then the shrinkage, which results from the cooling and 40 solidification of the interior, gives to the upper end of the ingot an irregular form, usually hollowing or cup-shaped, but for other or peculiar reasons the upper end of the ingot sometimes takes a bulging or dome shape. In either 45 case a portion of the upper end, or that which in the finished or subsequently-wrought product corresponds to the upper end of the ingot, has to be cut or sheared off as waste material; also, the shrinkage of the ingot usually 50 gives to the vertical or longitudinal sides of the ingot a slightly hollowing or concave shape, and the blooming operation has to be resorted

to, partly to reduce such irregularity and bring the ingot to a bloom form, either rectangular in cross-section, or bulging somewhat up and down the middle of the sides, or with flat sides 55 and beveled or rounded corners.

My present invention is directed to the elimination of these difficulties or objections, and I accomplish it wholly or in part by subjecting the metal immediately after pouring, and before complete solidification, and while still in the molds, to the action of one or more reducing or compressing rolls, whereby compression goes on at the same time with the shrinkage, 60 so that irregularities which otherwise would be caused by shrinkage or other agency are at once worked down, and an ingot is produced which has practically the perfect form of the bloom, and which also has no irregularly-shaped end, to be cut off and thrown away or 65 into the scrap-pile as waste material.

In what I now believe to be the best form of working my invention I employ two railway-tracks, R R', laid side by side in convenient proximity to each other and conveniently 70 near to the furnace, chamber, or hearth from which the molten metal is tapped, run, or poured out. On any suitable foundation along between the rails of one track, R, I lay one or more ingot-molds, a, but preferably a series 75 or row of them in line, end to end. These molds are of trough shape in cross-section, with closed ends, but open on top. The inner sides are inclined sufficiently, if need be, to insure a ready discharge of the completed ingot, and the dimensions may be as desired 80 with reference to the size of the ingot required. On the other track, R', I use a ladle, D, Figs. 1 and 3, of any suitable form or construction, mounted on a car-truck, D'. The 85 stopper-hole is closed by a stopper, d, of the usual form, and underneath the stopper-hole, and also supported on the car or truck frame, is a spout, d', which extends across to a point 90 immediately over the line of ingot-molds a, and with a delivery-hole, d'', therein, so that metal run out of the ladle may be run into the molds. The ladle, being filled or charged in any known way, is run onto the track R', and 95 on coming opposite the first mold of the series the stopper d is removed, and this and the following molds are filled, the ladle-car being 100

removed along with only the speed necessary to this end. The next part of the operation relates to the rolling or compression of the contents of the mold or molds while the same is undergoing change of form from shrinkage or otherwise, and in part, at least, before it fully solidifies. To this end I employ one, two, or more cars or trucks, B, and mount on, in, or to each car or truck frame one, two, or more rolls, c. These rolls are so set or adjusted by bearings, set-screws, &c.—such as are usual in the art—that their peripheries shall operate by a rolling and reducing or compressing effect on the surface of the metal in the molds a, the first or forward one compressing or working down on the surface of the metal—say one thirty-second or one sixty-fourth of an inch, more or less—and each succeeding one (if more than one are used) being set to work a little lower than the one forward of it—say by the same amount, more or less. The length of each rolling-surface, measured in the direction of the roll-axis, is, as near as may be, equal to the width of the top inside of the ingot-mold, as in Fig. 7, but must not bind seriously.

In making the rolls any suitable material may be employed; but to guard against the effects of the excessive heat of the metal I prefer to make the forward roll or rolls with a face of ganister, fire-clay, or other suitable refractory material, dried and baked, or otherwise suitably prepared. As one construction, I have shown the rolling-faces as made in an annular or ring form and slipped into the shafts; also, when so desired, I arrange on the forward end of the forward car a spool or drum, b, on which I wind a sheet or sheets of sheet iron or steel, and pay out the same as the roll-cars move along, so as to interpose the sheet between the rolls and the molten metal. This gives a partial protection as against heat, and also aids in getting and preserving a flattened face in the ingot, as against any tendency of its fluid or semi-fluid body to take some irregular form. The sheet acts as a protection to the steel as against oxidation, and also slightly as a chill to harden or set the upper face of the ingot; but, if so preferred, the sheets for this purpose may be cut to size and one be placed, by hand or otherwise, on top of each mold as soon as the mold is filled. The roll car or cars thus made and fitted are caused to move along the track R, following the pouring, so that as rapidly as the molds are filled the contents thereof shall be subjected to the action of the roll or rolls, as above indicated. Hence the rolling and cooling of the metal go on at the same time, so that as irregularities of shape in the ingot arise, as a result of cooling, such irregularities will be worked down, and when the ingot becomes fully solidified it will have regularly-shaped sides and ends, so that so much of the blooming operation as heretofore has been required to work down or out the cavities or other irregularities in the sides of the ingot will not be required. Also, in the in-

gots as I thus make them there is no irregularly-shaped end to be cut off as waste material, and the entire ingot can be worked into useful product. Also, this rolling action thus performed tends to express or press out of the metal and out of the mold those gases or gas-bubbles which are sometimes present in ordinary steel casting.

It will be observed that in working this invention with the best results the amount of reduction or compression given to each ingot should be as nearly as practicable equal or approximately equal to reduction of bulk caused by shrinkage or otherwise, so that, so far as possible, the exudation of metal over the sides of the mold (in case rolling is commenced before the surface chills) or forward from one mold to another will not ordinarily occur to any serious extent. The joints between molds may be protected by loam, as at r, Fig. 5, or in other desired way, such as will prevent the molten metal from getting down between the ends of the molds, and at the same time permit the rolls to pass readily and without injury from one mold to the next. In case the rolls sag or hang below the level of the tops of the molds an incline, r', Fig. 1, should be added at the end of the row of molds. The end walls of the molds should be a little lower than the sides, as shown—say about as much lower as the ingot is to be worked down or reduced by the action of the roll or rolls.

As thus far described, the rolls are intended to operate in compressing solely or chiefly by their own weight; but if before the last roll or the later operating-rolls have done their work the ingot shall in any case have become so far solidified that such weight is insufficient for effecting the compression described, then such roll or rolls, operating on what is practically a higher level, will lift the car from the track, or sustain a portion of its weight, so that the downward or compressive effect of such roll or rolls will be correspondingly increased by the amount of such weight taken off the track and thrown onto the roll or rolls. It will also be understood that the rolls rotate by friction as they are moved along, and that additional weights may be put on the cars, if desired. For the purpose of moving the ladle-car and the roll car or cars thus progressively and simultaneously along the tracks any suitable means may be employed—as, for example, a rope or chain, D², leading to a stationary engine or other motor, or a pushing-engine or locomotive, B'; but the power should be such in either case as is under ready control, especially as to speed, and such speed will be regulated by the condition of the work to be done. After the ingots have been thus made and worked I clear both tracks and run onto the track R' a crane-car, P, and a platform-car, P'. To move them a locomotive, B², or other motor, may be employed. On the crane-car P is a crane, n, preferably a hydraulic crane, having a flexible supply-pipe, regulating-cock, cyl-

inder, and piston, as shown, (Fig. 4,) together with other necessary appliances. The gib n' carries, by a flexible suspensory, a yoke device, n^2 , such as is usually employed in kindred operations. The yoke is connected with the ingot-molds a by means of trunnions a' , Figs. 2 and 4, and the molds are then hoisted, swung over the platform-car P' , the molds are inverted, one end swinging over between the pending chains of the yoke, and the ingot is deposited on the car, as indicated at a^2 , Fig. 2, and the empty ingot-mold is reset for another pour, as at a^3 . The ingots are thus emptied one after another and reset for another filling and rolling operation, as before.

In connection with the invention thus described or as yet to be described, I include all mechanical equivalents and all changes of devices and apparatus which involve substantially like methods of operation; but note should be made that in working this part of my invention I do not limit myself to the use of cylindrical rolls, for the rolling-faces may be made slightly concave in the direction of their length, or a fillet or bead may run around each cylindrical roll end, so as to make a bevel or rounded corner at each edge of the upper face of the ingot. This, in connection with a like fillet at the side corners of the bottom of the mold, will give an ingot somewhat more nearly the usual bloom shape, and such or other like modifications are hereby expressly included herein.

The method of operation described I apply not only to the production, as above set forth, of ingots of a bloom form or condition, which hence may be termed "bloom-ingots," but also to the production of what I term "billet-ingots." It is well known that ordinary blooms are by further working brought to some special form or shape, called "billets," as a preparatory step to the production of some article of commerce.

By carrying the improvements above described a step farther I am enabled to produce direct from the molten material in an ingot-mold an ingot-billet or an ingot in billet form, such that by the use of ordinary reducing and working rolls such ingot-billet can be worked into an article of commerce. This further step in the operation is illustrated in Sheet 3, where Fig. 8 is a view, partly in elevation and partly in longitudinal vertical section, of the roll-cars and rolls which I employ, together with the track and ingot-mold and metal therein. Fig. 9 is a transverse sectional view of one of the cars, track, and ingot-mold. Fig. 10 is a top view of the same sectioned through the middle adjusting-screws; and Figs. 11 to 16 are transverse sections through the ingot-mold and ingot, illustrative of the work done by the successive rolls.

Like letters indicate like parts, as in the previous sheets, and operating in like manner, except as hereinafter explained.

For convenience of illustration and descrip-

tion I have shown and will describe this part of my invention as applied to the making of ingot-billets for making channel-bars. For this purpose I use a single mold, a , of trough form, arranged between the rails of track R , as before. The proper amount of metal required for making the ingot-billet desired being ascertained, a movable dam-block, z , of proper size to fill the trough crosswise, is arranged at such point that so much of the mold-cavity as is back of such block will suffice to contain such amount of molten metal. Such metal is then run or poured into the ingot-mold a in the manner above described, or otherwise, and it is then ready for the rolling operation. For this purpose I employ a series of rolls, s s' s^2 s^3 , &c., in any desired number. The first of the series I make slightly convex in the direction of the length of its rolling-face, so that after it has been passed along over and has acted on the upper surface of the molten or unsolidified material the latter will have exactly or approximately the form in cross-section shown in Fig. 16. The surface of the metal is thus partially chilled or set, if not already so; but the next following roll has a collar, as shown, which works down irregularities resulting from shrinkage, and also works down the previously-formed depression, so as to bring the product to the shape substantially as shown in Fig. 14. While the metal is still cooling, approaching solidification, and shrinking it is acted on in like manner and for like-purposes by the next following roll s^2 , and so on by the successive rolls, as many as may be desired, until it is brought to the desired form in cross-section—say as in Fig. 11—which is a suitable billet form from which, by known methods of working, to make a channel-bar.

The number of rolls employed may be varied at pleasure; but preferably as many are employed as can be brought to act on the contents of any one ingot-mold before the same have fully solidified. While I have shown several such rolls I have done so chiefly to illustrate the probable extreme limit of the operation set forth. Ordinarily I will so shape the first roll of the series that, acting on the still plastic material, it will reduce it to the shape and approximately to the size required in cross section, and then use the following roll or rolls of the series merely to work down the irregularities resulting from cooling, as above set forth. The operation thus described will necessarily result in the elongation of the molten or partly molten body of metal, and hence as the first roll approaches the end of the mold in rolling the dam-block z is to be moved or slid along as fast as may be necessary to provide room for the forwardly-moving metal, and this may be done by a rope, z' , operated by a workman or otherwise.

By varying the forms of the rolls, and, if desired, of the ingot-molds, other irregular shapes of ingot-billets may be made by substantially the same operation, and more par-

ticularly such shapes as are known under the names of "H-iron," "T-iron," "I-bars," "angle-iron," &c. The rolls employed in this operation differ from those shown and described with reference to Sheets 1 and 2 in that some portion of the rolling-surface enters the body of the unsolidified or partly-solidified metal to such depth and in such manner as displacing it to destroy its otherwise substantial rectangular or bloom form; and the operation differs both in the respect thus suggested and in the fact that not only are irregularities caused in cooling obliterated by compression, as in Sheets 1 and 2, but at the same time the material is shaped, reduced, and elongated, and all before complete solidification takes place. Hence the method last described is included herein in its application to all the various shapes of billet product to which it is applicable.

It will also be within my invention to mount the roll or rolls in a suitable housing or frame and move the mold or molds along under such roll or rolls, other conditions being substantially the same. And I may also add that the ingot mold or molds may be arranged at the side of the track R, instead of between the rails, and the rolls may then project over the side of the car, though less advantageously; also, the molds may be arranged in curved order around a center, or an annular pan be employed with the necessary modifications in other parts; and, in fact, the ladle-car may be operated on the track R ahead of the roller-cars, if so preferred.

The blooms and billets produced by the operations described, in so far as they may involve patentable invention, will form the subject-matter of a separate application.

I am aware that it has been proposed to pass a heavy roller over the surface of cast-iron castings with reference to getting rid of blow-holes, as described in English Patent No. 714 of 1874; but my invention goes beyond this, and, in fact, belongs in a different department of metal-working, in that, (among other things,) first, it relates solely to cast malleable iron or steel, and not to cast-iron, which latter is not malleable; and, second, in that I not only compress the metal so as to express the gases, but also reduce it so as to change its form or lessen its size in cross-section.

I claim herein as my invention—

1. The method of making ingot-iron or steel ingot-billets by subjecting the metal while still in a fluid or semi-fluid condition, wholly or in part, and while inclosed in an open-topped box or trough, to the action of one or more rolls, some part of the operative face or faces of which operates beneath the otherwise even surface

of the metal, at the same time increasing the length of the trough, whereby the metal is reduced in cross-section, elongated and brought to the desired billet shape before complete solidification takes place, substantially as set forth.

2. The combination of a track, one or more ingot-molds arranged in line therewith, and one or more cars, each carrying one or more rolls, substantially as and for the purposes set forth.

3. A car carrying a series of two or more rolls, the lower operative face of each successive roll being slightly below the corresponding face of the previous roll, in combination with an open-topped ingot-mold adapted to receive the metal and present it to the action of such rolls before complete solidification takes place, substantially as set forth.

4. In combination with two parallel tracks, a series of ingot-molds arranged end to end along one line of tracks, a rolling mechanism operated along the same line of track to compress the metal while cooling, and a hoisting and dumping mechanism operated along the other line of tracks to hoist, empty, and replace such ingot-molds for another filling, substantially as set forth.

5. The combination, on the same car, of rolls and sheet-iron cooling and feed drum b, substantially as set forth.

6. In combination with a roll or rolls arranged to operate on the metal of an ingot-mold before complete solidification, a sheet-metal sheet interposed between the roll or rolls and the metal in the mold, substantially as set forth.

7. In combination with a series of open-topped ingot-molds, a, a loam-covering, r, at the meeting joints of the molds, substantially as set forth.

8. In combination with an open-topped ingot-mold, a movable dam-block, z, substantially as set forth.

9. In combination with a car or truck and a track and one or more molds arranged along the track, a series of two or more rolls arranged on the car or truck and adjusted at the proper level for reducing the metal in the molds, substantially as described, with reference to adding the weight of the car to the weight of the rolls, as the resistance to reduction increases in the ingot.

In testimony whereof I have hereunto set my hand.

WILLIAM HAINSWORTH.
